CLAIM

I claim the ornamental design for a cosmetology and barbing glove, as shown and described.

DESCRIPTION

FIG. 1 is a top, perspective view of a cosmetology and barbing glove, showing my new design.

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of a hand in FIG. 1 depicts environment and forms no part of the claimed design. All other broken lines in the drawings illustrate portions of the article and form no part of the claimed design.
